VIBRATORY MASSAGE UNIT

Joseph R. Mango, Midlothian, Ill., assignor to Tractoy,
Inc., Dubuque, Iowa, a corporation of Iowa

Filed Oct. 20, 1958, Ser. No. 53,032

Term of patent 3½ years

(Cl. D83—1)

Figure 1 is a perspective view of a vibratory massage unit embodying my new design;

Figure 2 is a left side elevation thereof;

Figure 3 is a front elevation thereof;

Figure 4 is a top plan view thereof;

Figure 5 is a rear elevation thereof; and

Figure 6 is an enlarged vertical cross section thereof taken through the center of the housing.

The dominant features of my design reside in the full line portions of the drawing. The broken line showing of a belt has been omitted from Figures 2, 3, 4 and 5 for convenience of illustration.

I claim:

The ornamental design for a vibratory massage unit, as shown and described.
